UNITED STATES PATENT OFFICE.

ETHEN D. MANTONYA, OF UTICA, OHIO.

DESIGN FOR A RUBBING-HEAD FOR WASHING-MACHINES.

SPECIFICATION forming part of Design No. 16,317, dated October 6, 1885.

Application filed August 28, 1885. Serial No. 175,606. Term of patent 14 years.

To all whom it may concern:

Be it known that I, ETHEN D. MANTONYA, a citizen of the United States, residing at Utica, in the county of Licking and State of Ohio, have invented and produced a new and original Design for Rubbing Heads or Boards of Washing-Machines, of which the following is a specification.

The feature of my design consists of a rubbing head or board the ends of which are of partly-circular form scalloped on their convex edges, and the body of which presents a series of cylindrical figures in rows between the opposite scallops of said ends, and of successively small and large diameters throughout their length.

Reference is to be had to the accompanying drawing, which forms a part of this specification, and which represents a view in perspective of a washing-machine rubbing head or board embodying my design.

A A are the ends of the rubbing-head, partly of circular form, ornamented by scallops a a on their convex edges, and of straight and concave configuration, as at b and c c, at the termination of the scallops. The body of the rubbing-head presents a series of parallel cylind-

rical figures, B B, between the opposite scallops of the ends A A, and of successively small and large diameters throughout their length, as at d e, thereby presenting the appearance of a series of circular bars with a succession of cylindrical swells on them. These cylindrical figures B B are concentric with the scallops a a, and present a circular termination, as at f, on the outer sides of the ends A A, thereby giving the appearance of eyes to the scallops.

I claim—

The design for the rubbing head or board of a washing-machine, herein shown and described, the same consisting of the scallops a a, of circular form on the convex edges of the ends of the head, and of a body part between said ends presenting the appearance of a series of parallel cylindrical figures, B, of varying diameters throughout their length, as at d e, and concentric with the scallops, and terminating in circular figures f on the exterior of the scallops.

ETHEN D. MANTONYA.
